No. 36,505.

Patented August 18, 1903.

UNITED STATES PATENT OFFICE.

CHARLES EDWARD HAVILAND, OF LIMOGES, FRANCE.

DESIGN FOR A PLATE, DISH, OR SIMILAR ARTICLE.

SPECIFICATION forming part of Design No. 36,505, dated August 18, 1903.

Application filed July 21, 1903. Serial No. 166,506. Term of patent 7 years.

To all whom it may concern:

Be it known that I, CHARLES EDWARD HAVILAND, a citizen of the United States, residing at Limoges, in the Republic of France, have 5 invented a new, original, and ornamental Design for a Plate, Dish, or Similar Article, of which the following is a specification, reference being had to the accompanying drawings, forming a part thereof, and in which—
10 Figure 1 is a top elevation of a plate or dish bearing and incorporating my design, and

Fig. 2 is a vertical section through a portion of same on the dotted line 2 2 of Fig. 1.

What I claim is—

The ornamental design for a plate, dish or 15 similar article, substantially as shown.

Signed at Limoges, in the Republic of France, this 9th day of July, A. D. 1903.

CHARLES EDWARD HAVILAND.

Witnesses:

F. CATE,
A. BOUCHE.
